MACHINE TO RIVET TWENTY LONG SPOKES
WITH HUB AND RIM TOGETHERHerman Tormyn and Frank F. Wiethoff, Detroit,
Mich., assignors to General Motors Corporation,
Detroit, Mich., a corporation of Delaware

Application July 29, 1932, Serial No. 625,999

11 Claims. (CL. 78—16)

This invention relates to the manufacture of wire wheels used on automotive vehicles and has particular reference to the die for securing the long spokes between the hub shell and the rim.

5. The machine or die of the invention is one of ten and in its sequence of operation follows the die or machine of our copending application, Serial No. 625,998, filed July 29, 1932.

The die of the invention comprises a low die 10 shoe and a top die, the top die being movable to and from the die shoe. A pad is yieldably mounted in the die shoe and has yieldably mounted thereon a positioning ring for the support of the hub shell and a second positioning ring rigidly

15 mounted thereon to support the rim. Suitable anvils on the rim supporting ring are used to position and hold the spokes. A plurality of punch holders having punches mounted therein are slidably mounted at the pad and each punch holder 20 has a link pivoted thereto which link is pivotally mounted at its free end so that when the pad is moved downwardly the link will force the punch holders inwardly toward the rim to cause the punches to head the spoke ends.

25 A suitable fixture is positioned inside the wheel hub prior to the placing of the assembly in the die, the fixture having a plurality of backing members which support the heads of the spoke and firmly force the heads into the spoke openings when the punches are operated.

The top die is provided with a plunger at its central portion which engages with the hub shell and with a spreader to force the backing member against the hub shell. Immediately over 35 the rim hub the top die is provided with an anvil holding ring which supports a plurality of anvils which cooperate with the anvils on the pad of the die shoe. The anvils rigidly hold the spokes adjacent the rim during the action of the punches 40 to head the spoke ends. A suitable rubber pad between the anvil holding ring and the top die serves to equalize the pressure on all of the anvils so that the spokes are gripped and held with a uniform pressure.

45 On the drawings:

Figure 1 is a front view of a press showing the invention applied thereto.

Figure 2 is a side view of the structure of Figure 1.

50 Figure 3 has an enlarged sectional detailed view through the die taken substantially on the line 3—3 of Figure 5.

Figure 4 is an enlarged sectional detailed view similar to Figure 3 but with the top die separated 55 from the die shoe.

Figure 5 is a plan view taken substantially on the line 5—5 of Figure 4.

Figure 6 is a detailed view in plan of a portion of the fixture.

Figure 7 is a perspective view of one of the punch holders.

Figure 8 is a perspective view of a locator used on the dies.

Figure 9 is a perspective view of one of the backing members used on the fixture.

Figure 10 is a perspective view of the top retaining ring of the fixture.

Figure 11 is a perspective view of the retaining ring.

Referring to the drawings, the numeral 2 indicates the upright frame of the press. On the frame there is mounted the source of power 4 such as an electric motor having the pulley 6 to drive the belt 8. The belt 8 in turn drives the flywheel 10 and the shaft 12. The shaft 12 extends through the machine and the other side has a pinion (not shown) secured thereto which drives a large wheel 14 rigidly mounted on the shaft 16 having a crank 18 intermediate its ends and working in the frame 2. The crank 18 has the connecting rod 20 mounted thereon which is suitably connected to a crosshead 24 which is in turn connected to the top shoe 26 of the die 28. The lower shoe of the die is indicated at 30 and has the hydro-pneumatic cylinder 32 having a suitable piston (not shown) connected by a piston rod 34 to a plate 36. The plate 36 is in turn connected by means of the rods 38 to the plate 40 on which there rest the pressure pins 42. The cylinder 32 is of the hydro-pneumatic type and is provided with a suitable pipe system to allow ingress and egress of the air and liquid in timed relation with the action of the press. The plates 36 and 40 are slidable in the base of the press 30.

The crosshead 24 also has a hydro-pneumatic cushion which includes an air pipe 44 leading to an air chamber 46 having the piston 48 therein and an oil line 50 leading to a chamber 52. A partition 54 separates the chambers 46 and 52 and suitable passages (not shown) are provided in the partition to allow the oil to flow from one chamber to the other. The piston 48 has a stem 56 the end of which is bored and which extends through a partition indicated at 60. There is a spring loaded check valve at the end 50 of the bore at 62. The head end 62 is adapted to contact with the piston 64 at the lower part of the chamber 52. A suitable coil spring 66 between the head 62 and the partition 60 constantly urges the piston 48 and stem 56 down.

wardly. The parts described are mounted in a cylinder 68 formed on the cross head 24. Excessive pressure below the partition will crack the check valve to allow liquid to flow to the 5 chamber 52.

An operating handle 70 adjacent the front of the machine operates a linkage 72 to operate a clutch to throw the wheel 14 into operation. The clutch is so arranged that after one rotation of 10 the crank 18 the machine will stop and the clutch must again be thrown into operation by the movement of the handle 70. A stop brake is shown at 74 with the brake shoes 76 and the operating linkage 78.

15 The parts so far described and their operation are conventional and per se form no part of the invention.

Referring to Figures 3 and 4 the die shoe 30 comprises the flat bottom plate 80 having secured 20 to the outer periphery thereof the upper and lower pivot forming rings 82 and 84 rigidly mounted on the bottom plate 80 by means of the machine bolts 86. In their inner meeting line the rings 82 and 84 are formed with the circular bearing 25 surfaces 88 and 90 to receive the rounded bearing heads 92 of a link 94, the purpose of which will later be described.

The rings 82 and 84 have suitable openings 30 with bearings 96 therein to receive the guiding studs 98 secured to the top die 26. Suitable spacing blocks 100 are secured to the guiding studs 98 to limit the movement of the top die 26 on the lower die shoe 30.

35 The plate 80 of the die shoe 30 and the inner periphery of the ring 84 form a bearing surface as indicated at 102 and in which there is slidably received the pad 104. The bottom plate 80 has suitable openings through which project the plungers 42 and strike against the bottom pad 40 and constantly urge the pad upwardly as shown in Figure 4. The pad has a positioning or locating ring plate 106 mounted at its center and held thereon by means of the shoulder 108 on a rim 45 positioning ring 110 secured to the pad by means of the machine bolts 112. The positioning ring 106 is slidably mounted in the ring 110 and is resiliently mounted relative to the plate by means of a plurality of coil springs 114 held in cooperating recesses in the pad 104 and positioning ring 50 106. The upper outer periphery of the positioning ring 106 is shaped to receive the hub shell 116 and to serve as a backing for the heads of the short spokes 118.

55 Secured to the upper portion of the rim positioning ring 110 are ten anvils 120. Each anvil has a pair of steps 122 and in each step there is a groove 124 to receive the end of the long spokes 126. The structure of the anvils is best shown in Figure 4. The outer side of the anvils as well as 60 the upper outer portion of the rim retaining ring 110 is shaped as at 128 to receive the lower portion of the rim.

65 At its upper portion at the outer periphery thereof the pad 104 is provided with ten radial grooves 130 in each of which there is slidably mounted a punch holder 132. The punch holders are held in position by the top retaining ring 134 having a plurality of prongs or teeth 136 which 70 project downwardly to the pad 104 and are positioned between the punch holders 132. The ring 134, prongs 136, and grooves 130 form a slide for the punch holders 132. Each punch holder has two punches 138 mounted therein each held in 75 place by a set screw 140.

The rear portion of each punch holder is recessed as indicated at 142, and a pivot pin 144 pivots the end of the link 94. The end face of each link 94 at 145 is machined and cooperates with a correspondingly machined surface on each punch holder. These two machined surfaces take the thrust when the punches are moved toward the rim or inwardly of the die, the pin 144 being used only to withdraw the punch holders. 5

10 Suitable guide pins 146 rigidly secured in the base 80 and operating in bearings 148 at the pad 104 guide the pad relative to the base 80.

Prior to placing the assembled hub shell spokes and rim in the die shoe a fixture indicated as a 15 whole at 150 is placed in the hub shell. The fixture comprises the base block 152 (Figure 6) having ten recesses 153 in its top portion for the purpose of receiving the ten backing members 154 shown in perspective view in Figure 9. 20 Each backing member 154 has a pin 156 rigidly secured in an opening 158 at its innermost end and a coil spring 158 held in a passage in the block 152 by a plug 160 and which presses against the pin and constantly urges the pin and backing 25 member 154 toward the center of the fixture 150. A top plate 162 shown in perspective in Figure 10 is secured over the base block 152 and holds the backing members 154 slidably in position. Suitable recesses 164 in the periphery of the top plate 30 162 allow the positioning pins 167 at the top outer end of the block to move with the backing members 154 inwardly of the fixture.

The base block 152 has a central opening 166 through which there passes the shank 168 of a 35 cam headed bolt screwthreaded at its end into a cam or spreader 170. The shank 168 is allowed a considerable movement in the opening 166 so that the spreader or cam 170 may be withdrawn away from the backing members 154 to allow the 40 springs 158 to force them inwardly of the fixture. The spreader 170 is reciprocal relative to the fixture and may be pushed downwardly thereinto as shown in Figure 3 to spread the backing elements 154 against the heads of the long spokes 126. 45 Each backing element 154 accommodates two spokes.

The top shoe has the plunger 172 rigidly secured to the piston 64 by means of a machine bolt 174. The plunger is slidable in the top die 26 and has 50 the head 176 adapted to strike against the spreader or cam 170, and the striker ring 178, the lower portion of which is suitably shaped as indicated at 180 to strike against the smaller portion of the hub shell 116 as shown in Figure 3. 55

60 Inner and outer retaining rings 182 and 184 are secured to the top die by means of the machine bolts 186. The rings 182 and 184 have shoulders 188 which cooperate with shoulders 190 on an anvil holding ring 192 slidably to mount the ring 65 relative to the top die 26. A rubber ring or pad 194 is positioned between the top die 26 and the anvil ring 192 to form a resilient mounting for the ring. Anvils 120' are secured to the lower portion 70 of the ring and have the stepped portions 122' and the grooves 124' the grooves being shaped to fit over the ends of the long spokes at the rim. The anvils 120 and 120' mate or cooperate with each other, that is, when the top die 26 is moved 75 toward the die shoe 30 the anvils will mate with each other so that the ends of the long spokes will be received between the cooperating grooves 124 and 124' rigidly to hold the spokes at the rim. The anvils 120 and 120' never contact but are 75

always slightly spaced when the spoke is there-between so that the grooves 124-124' will rigidly and tightly grip each spoke. The rubber pad 194 equalizes the pressure so that all spokes are held 5 under the same pressure.

A locator 196, shown in perspective in Figure 8, is positioned between two of the anvils on the rim positioning ring 110. The top portion of the locator 196 is rounded as shown at 198 and tapered as 10 at 200 and has the wing portions 202 at its lower inner part. The purpose of this locator is accurately to position the assembled shells, spokes, and rim in the die shoe. When the assembly is placed in the machine the locator 196 is received 15 between two of the short spokes as shown in Figure 5. The rounded portion 198 will allow the wheel readily to slip over the locator and the beveled portion 200 to accommodate the blend in the short spokes adjacent the rim. The short 20 spokes will be received on the tops of the wings 202. But one of these locators may be used and it is so positioned that the ends of the long spokes accurately will be received in the grooves 124-124' of the anvils 120-120'.

25 A pair of hook members 204 at diametrically opposite points is secured to the top die 26 and the purpose of the hooks is to raise or withdraw the wheel from the lower die after the spokes have been headed. Each hook 204 has the elongated 30 recessed opening 206 at its lower portion in which the arm 208 is pivoted on a pin 210. The arm 208 has the beveled underside 212 and the tooth 214. The coil spring 216 mounted in a passage 218 in the hook is secured to the outermost end of the arm at 220 and constantly urges the outer end upward or the inner end downward. When the top die descends in the lower die the beveled portions 212 will ride over the top flange of the rim and when the hook passes the flange the spring 40 will pull the tooth 214 downwardly so that it will catch under the rim. When the top die is raised the arms 208 at opposite sides of the top die will raise the wheel upward therewith. To remove 45 the wheel from the machine the operator may pull it toward him. After the wheel is taken from the machine it is inverted to allow the fixture 150 to fall from the shell.

The retaining ring 134 is provided with suitable recesses at diametrically opposite points, as indicated at 222 to accommodate the hook member 204.

50 The operation of the die is as follows: assuming that the die shoes are in the position shown in Figure 4 and that the assembled hub shell, rim, spokes and fixture are positioned in the lower die shoe the operator moves the handle 70 to cause the crank 18 to make one revolution. This will cause the top shoe 26 to descend on the die shoe and bring into contact the head 176 with the spreader or cam 170 to cause the spreader to force the backing members 154 rigidly against the heads of the long spokes in the wheel shell. Only the pneumatic force of the upper hydro-pneumatic cushion is now acting on the plunger 65 172. The striker ring 178 will strike the end of the hub shell and the plunger and ring 178 will force the ring plate 106 downwardly against the tension of the coil spring 114. This will stretch the short spokes a little or place them under tension which continues until the long spoke ends are headed and the top shoe rises, when the tension is released and distributed over all the spokes. Further movement of the top die will be 70 under the full force or resistance of the upper hydro-pneumatic cushion and will press the anvil

ring 192 with its anvils 120 in contact with spokes in the anvils 120 rigidly to grip the spoke ends immediately behind the rim. The resistance of the pneumatic part of the lower hydro-pneumatic cushion will now begin to act. The rubber pad 5 194 will be compressed and equalize the pressure all around so that the anvils will have the same pressure on the spokes. The continued downward movement of the top shoe will now force the pad 104 downwardly against the full pressure 10 exerted on the pins 42 by the lower hydro-pneumatic cushion. This downward movement will swing the links or arms 94 to cause the punch 15 holders 132 to move inwardly in their slides or grooves and cause the punches 138 to strike the ends of the long spokes 126 to head the same and rigidly secure them to the rim. The spacers 100 will limit the downward movement of the top shoe relative to the die shoe and prevent damage to the parts caused by excessive pressure thereon. 20 The lowermost position of the crank 18 occurs when the spacers strike the ring 82. When the top shoe 26 rises, the hooks 204 will be behind the edge of the rim and will raise the rim therewith to the position shown in Figure 4. 25

We claim:

1. In a machine for simultaneously riveting a plurality of long spokes between the hub shell and rim of a wire wheel, said wheel previously having the short spokes riveted in place, a die shoe including a pad reciprocably mounted thereon, anvils mounted on said pad to position the long spokes adjacent the rim and to receive the short spokes, a plurality of punch holders 30 slidable on the pad to and from the rim adjacent the anvils, punches in said holders movable with the holders to head the spoke ends, means to cause the punch holders to move toward the rim, a top shoe, an anvil ring on said shoe, a plurality of anvils on said ring cooperating with the pad anvils rigidly to hold the long spokes, and means to cause the top shoe to move toward the die shoe to cause the anvils tightly to grip the spokes and to reciprocate the pad to cause said means to move the punches toward the rim 45 to head the spokes.

2. In a machine for simultaneously riveting a plurality of long spokes between the hub shell and rim of a wire wheel, said wheel previously having the short spokes riveted in place, a die shoe 50 including a pad mounted thereon, anvils mounted on said pad to position the spokes adjacent the rim, a plurality of punch holders slidable on the pad to and from the rim adjacent the anvils, punches in said holders movable with the holders to head the spoke ends, means to cause the punch holders to move toward the rim, a top shoe, an anvil ring on said shoe, resilient means between the top shoe and ring, a plurality of anvils on said ring cooperating with the pad 55 anvils rigidly to hold the long spokes, and means to cause the top shoe to move toward the die shoe to cause the anvils tightly to grip the spokes and to cause the operation of said first named means to move the punches toward the rim to 60 head the spokes.

3. In a machine simultaneously to rivet all the long spokes of a wire wheel between the hub shell and the rim, a die shoe including a resiliently mounted pad, said pad having a resiliently 70 mounted member to receive the hub shell, means on the pad to receive the long spokes adjacent the rim, means to back the long spoke ends inside the hub shell, a top die reciprocable relative to the die shoe and adapted when reciprocated 75

- to move the pad and to press said member tightly against the pad, means on the top die cooperating with the spoke receiving means of the pad rigidly to hold the long spoke ends, punches mounted on the pad, said die shoe having means to force the punches toward the rim to head the long spoke ends, said last named means being operative only when the pad is moved.
4. In a machine simultaneously to rivet all the long spokes of a wire wheel between the hub shell and the rim, a die shoe including a resiliently mounted pad, said pad having a resiliently mounted member to receive the hub shell, means on the pad to receive the long spokes adjacent to the rim, means to back the long spoke ends inside the hub shell, a top die reciprocable relative to the die shoe and adapted when reciprocated to move the pad and press said member tightly against the pad, means on the top die cooperating with the spoke receiving means of the pad rigidly to hold the long spoke ends, punches mounted on the pad, said die shoe having means to force the punches toward the rim to head the long spoke ends, said last named means being operative only when the pad is moved, and means on the top die to withdraw the wheel from the die shoe when the spokes have been riveted.
5. In a machine simultaneously to rivet all the long spokes of a wire wheel between the hub shell and the rim, a die shoe including a resiliently mounted pad, said pad having a resiliently mounted member to receive the hub shell, a plurality of anvils on the pad to receive the long spokes at the rim, means to back the long spoke ends inside the hub shell, a top die reciprocable relative to the die shoe and adapted when reciprocated to move the pad to press said member tightly against the pad, anvils on the top die mating with the anvils of the die shoe and adapted simultaneously to grip and hold the long spoke ends at the rim, punches mounted on the pad, said die shoe having means to force the punches toward the rim to head the long spoke ends, said last named means being operative only when the pad is moved.
6. In a machine simultaneously to rivet all the long spokes of a wire wheel between the hub shell and the rim, said wheel having a plurality of short spokes riveted in place, a die shoe including a resiliently mounted pad, said pad having a resiliently mounted member to receive the hub shell, said member being shaped to contact with and back the ends of the short spokes during the riveting of the long spokes, means on the pad to receive the long spokes at the rim, means to back the long spoke ends inside the hub shell, a top die reciprocable relative to the die shoe and adapted when reciprocated to move the pad and press said member tightly against the pad, means on the top die cooperating with the spoke receiving means on the pad rigidly to hold the long spoke ends, punches mounted on the pad, said die shoe having means to force the punches toward the rim to head the long spoke ends, said last named means being operative only when the pad is moved.
7. In a machine simultaneously to rivet the long spokes of a wire wheel between the hub shell and the rim, a die shoe including a resiliently mounted pad, said pad having a resiliently mounted member to receive the hub shell, means on the pad to receive the long spokes at the rim, means to back the long spoke ends inside the hub shell, a top die reciprocable relative to the die shoe and adapt-
- ed when reciprocated to move the pad and press said member tightly against the pad, means on the top die cooperating with the spoke receiving means on the pad rigidly to hold the long spoke ends, means on the top die simultaneously to press the hub shell spokes and rim tightly against the die shoe when the top die is moved, punches mounted on the pad, said die shoe having means to force the punches toward the rim to head the long spoke ends, said last named means being operative only when the pad is moved.
8. In a machine for simultaneously riveting a plurality of spokes of a wire wheel, said wheel having a hub shell and a rim, said hub shell having different diameters at its ends at the place of connection of the spokes, said wheel previously having riveted in place all of the spokes at one hub diameter, a die shoe including a resiliently mounted means for receiving the rim, hub shell, and spokes, a top die movable to and from the die shoe, cooperating anvils on both shoes tightly to grip the unriveted spokes at the rim and rigidly to hold the same while the spokes are being riveted, a plurality of punch holders in said means slidable to and from the rim, punches in said holders, said die shoe having means to cause the holders to move toward the rim to cause the punches to head the unriveted spokes, and means operated by the movement of the top die toward the die shoe to press down the resiliently mounted means to cause the means for moving the punch holders to operate.
9. In a machine for simultaneously riveting a plurality of spokes of a wire wheel, said wheel having a hub shell and a rim, said hub shell having different diameters at its ends at the place of connection of the spokes, said wheel previously having riveted in place all of the spokes at one hub diameter, a die shoe including a resiliently mounted means for receiving the rim, hub shell, and spokes, a top shoe movable to and from the die shoe, cooperating anvils on both shoes tightly to grip the unriveted spokes at the rim and rigidly to hold the same while the spokes are being riveted, a plurality of punch holders slidable in said means to and from the rim, punches on said holders, said die shoe having means to cause the holders to move toward the rim, and means operated by the movement of the top die toward the die shoe to press down the resiliently mounted means to cause the means for moving the punch holders to operate, and means in the hub rigidly to back the spoke ends while the punches are operated.
10. In a machine for simultaneously riveting a plurality of spokes of a wire wheel, said wheel having a hub shell and a rim, said hub shell having different diameters at its ends at the place of connection of the spokes, said wheel previously having riveted in place all of the spokes at one hub diameter, a die shoe including a resiliently mounted means for receiving the rim, hub shell and spokes, a top die movable to and from the die shoe, cooperating anvils on both die shoe and top die tightly to grip the unriveted spokes at the rim and rigidly to hold the same while the spokes are being riveted, a plurality of punch holders slidable in said die shoe to and from the rim, punches in said holders, said die shoe having means to cause the holders to move toward the rim to cause the punches to head the spoke ends, and means operated by the movement of the top die toward the die shoe to press down the resiliently mounted means to cause the means for moving the punch holders to operate.

and means on the top die to withdraw the riveted spoke wheel from the die shoe when the top die moves away from the die shoe.

11. In a machine to rivet a plurality of spokes of a wire wheel, said wheel having a hub shell and a rim, said hub shell having different diameters at its ends at the place of connection of the spokes and said wheel having riveted in place all of the spokes at one hub diameter, a die shoe including means for receiving the wheel, a top shoe movable to and from the die shoe, means

on said shoes for stretching or placing the riveted spokes under tension when the top shoe moves onto the die shoe, and means for riveting the unriveted spoke ends while the riveted spokes are under tension, said riveted spokes being relieved of their tension when the top shoe moves away from the die shoe, equally to distribute the tension among all the spokes.

HERMAN TORMYN.

FRANK F. WIETHOFF.
